MAGNIFYING GLASS

Frank J. Gubics, Cleveland, Ohio

Application April 12, 1950, Serial No. 9,159

Term of patent 14 years

(Cl. D57—1)

To all whom it may concern:

Be it known that I, Frank J. Gubics, a citizen of the United States and a resident of Cleveland, in the county of Cuyahoga and State of Ohio, have invented a new, original, and ornamental Design for a Magnifying Glass, of which the following is a specification, reference being had to the accompanying drawings, forming a part hereof.

In said drawings, Fig. 1 is a perspective view of the magnifying glass showing my new design, the magnifying element being enclosed within the protective casing therefor, in which it is slidably mounted, and thus being in a non-operative position; and Fig. 2 is a perspective view of said glass with the magnifying element projecting

from the casing and thus being in operative position.

I claim:

The ornamental design for a magnifying glass, as shown and described.

FRANK J. GUBICS.
